FIRING MECHANISM FOR FIREARMS

Charles H. Barnes, Bridgeport, Conn., assignor to
Remington Arms Company, Inc., Bridgeport,
Conn., a corporation of Delaware

Application June 13, 1944, Serial No. 540,015

5 Claims. (Cl. 42—3)

1

The present invention relates to firing mechanism for firearms, and, in particular, to an improved autoloading rifle for .22 caliber short and long rifle cartridges.

An object of the invention is to provide an improved firearm which is relatively inexpensive and one which may be readily assembled and dismounted without the use of tools or other special equipment. A further object is to provide an automatic rifle having a receiver constructed from sheet metal. A still further object is to provide an autoloading rifle having an improved fire control mechanism and feed means for selectively feeding cartridges from a magazine into the chamber of the barrel.

These and other objects, features and advantages of the invention will be described in more detail in the specification which for the purposes of illustration discloses an autoloading rifle for .22 caliber cartridges. It will be understood, however, that the invention is not limited to the embodiment shown but is applicable to firearms of other calibers and includes all modifications within the scope of the appended claims.

In the drawings:

Fig. 1 shows a side elevation partly in section of the autoloading rifle of this invention including the tubular magazine.

Fig. 2 is a side elevation partly in section of the sheet metal cover and trigger plate which comprise the receiver.

Fig. 3 is a fragmentary plan view of the rear end of the trigger plate showing its laminated structure and including the sear lug insert and butt stock stud.

Fig. 4 is a cross section of the receiver on line 4—4 of Fig. 1.

Fig. 5 is a sectional plan view of the receiver including the breech bolt, the cartridge carrier, the firing pin and the breech end of the barrel in the horizontal plane of line 5—5 of Fig. 4.

Fig. 6 is an elevation in section of the receiver on line 6—6 of Fig. 4 showing the action open, and including the fire control mechanism and the carrier latch arm. The trigger is shown in its rear-most or fired position.

Fig. 7 is similar to Fig. 6 but with the action closed and not including the carrier latch arm. The full line position of the trigger is its firing position, the dotted line position being its fired position.

Fig. 8 is a fragmentary sectional elevation on line 8—8 of Fig. 6, showing the carrier latch in its locked and unlocked positions.

Fig. 9 is a plan view of the fragmentary sec-

2

tional view of Fig. 8 in the horizontal plane of line 9—9 showing the camming action of the breech bolt in unlocking the carrier latch.

Fig. 10 is a fragmentary plan view taken on the section line 5—5 of Fig. 4 showing the position of the extractor when the action is closed.

Fig. 11 is a plan view of the cartridge carrier including the cartridge stop and carrier latch, the trunnions of the carrier being shown mounted in the slots in fragmentary portions of the sides of the trigger plate.

Fig. 12 is a front end elevation of the carrier of Fig. 11 showing the resilient jaws.

Fig. 13 is an exploded view in perspective of the fire control mechanism including the trigger safety lock.

Fig. 14 is a section in elevation on line 14—14 of Fig. 7.

Fig. 15 is an end elevation of the receiver in the direction of the arrows 15—15 of Fig. 2.

Referring to the drawings, Fig. 1 shows an autoloading rifle comprising, in general, a butt stock 20, fore-stock 21, receiver 22 and barrel 23, cartridges being automatically fed into the chamber of the barrel from a tubular magazine indicated by the dotted lines 24 which is mounted in the butt stock and supplied with bullets through a suitable aperture therein. The magazine including the cartridge follower and the bayonet fastening means for securing the magazine in the stock are of well known construction and are illustrated in greater detail in the patent to Browning, No. 1,038,384, January 6, 1914.

The receiver of the firearm comprises a trigger plate 25 and a cover 26, as shown in Figs. 2 and 14. Both the trigger plate and cover are constructed from sheet metal. The trigger plate is trough-shaped in cross section having substantially vertical sides 27 struck up from a substantially flat sheet of metal. The upper edge 27' of each side 27 comprises a guide rail for slidably supporting a breech bolt hereinafter described and is provided with a U-shaped slot 28 for pivotally supporting the trunnions of a cartridge carrier as described below.

The rear end of the trigger plate comprises a laminated wall 29 formed by folding a rearwardly extending portion 29' of each side wall 27 in overlapping relationship, see Fig. 3, and welding the overlapped portions together. The rear wall also embodies a third substantially rectangular plate 30 welded to the front face of the overlapped portions 29' and provided at its upper end with a pair of forwardly extending spaced substantially parallel bracket members 32. The latter

may be formed separately and fastened to the plate 30 or, as shown in the drawings, may be formed integrally therewith by making a transverse cut 30' in opposite edges of the plate 30 and bending the cut portions inwardly and forwardly. The brackets 32 are provided with transverse axially aligned apertures 33 for pivotally supporting a sear as hereinafter described.

The laminated rear wall 29 is provided with two vertically superposed apertures 34 and 35, see Figs. 2, 6 and 7, the upper aperture 34 being adapted to receive a butt stock stud 36 and the lower aperture 35 being adapted to receive and support the magazine tube 24. The butt stock stud 36 comprises a substantially cylindrical sleeve having a reduced portion 36' at its forward end provided with a counterbore 37. The stud 36 is fixedly secured in the laminated rear wall of the trigger plate by seating the reduced end 36' of the stud in the aperture 34 and swaging over the edges of the counterbore 37. The magazine tube 24 extends through the aperture 35 in the rear wall 29 and is securely held in proper position therein by means of a self-locating bushing 38 which is mounted on the magazine 24 and has an arcuate flange portion 39 adapted to partially embrace the underside of the stud 36. A screw 40 is provided for securing the bushing 38 to the rear wall of the receiver.

At the rear end of each side plate 27 and adjacent the lower edge thereof is a transverse projection 40 which may be circular in cross section or substantially rectangular, as shown in Figs. 2 and 3, and provided with tapered forward edges. The projections 40 are adapted to lock the cover to the trigger plate as hereinafter described.

The bottom 42 of the trigger plate is substantially rectangular and provided with a relatively wide rectangular aperture 43 adjacent its rear end for accommodating a trigger. A somewhat narrower slot 44 extends forwardly from the front edge of the trigger slot 43 and constitutes a guide slot for the trigger lock or safety. A second relatively wide and substantially rectangular aperture 45, see Fig. 4, is formed in the forward end of the bottom of the trigger plate, a portion of the metal forming the slot being struck up to provide a substantially vertical web 46 at the rear end of the aperture 45. The web 46 is provided with an arcuate upper edge 46' adapted to support the forward end of the tubular magazine 24, see Figs. 2, 6 and 7, and has an aperture 47 adjacent its base for securing the hooked end 48 of the trigger guard 48 thereto. The rear end of the trigger guard is shown secured by a screw 49 to a rearwardly extending tang 50 on the bottom of the trigger plate. A second aperture 47' is provided in the web 46 immediately above the aperture 47 for receiving the trigger spring hereinafter described.

The forward end of the trigger plate 25 is provided with a barrel lug insert 52 which comprises a relatively solid substantially rectangular block of metal having a smooth barrel receiving aperture 53; and a stem portion 54 extending downwardly at substantially right angles to the longitudinal axis of the aperture 53, the stem being provided with a reduced counterbored portion 55. The latter is adapted to seat in an aperture 56 in the forward end of the trigger plate bottom and to be fastened therein by swaging. Referring to Fig. 15, the lower end of the stem portion 54 of the lug is somewhat narrower than the upper end of the lug thereby forming shoul-

ders 57 which are adapted to fit over the upper edges 27' of the sides of the trigger plate. The joints between the shoulders 57 and the upper edges of the sides 27 are welded or soldered for securely fastening the lug in the forward end of the trigger plate. A substantially horizontal ledge 58 is formed integrally on the back of the lug 52 while the front of the lug comprises a bevelled or downwardly sloping surface 59. The stem portion 54 is apertured as at 60 and tapped for securing a barrel fastening bolt 61 therein.

Referring to Figs. 6 and 7, the breech end of the barrel 23 is reduced to provide a smooth wrist portion 62 which is adapted to make a nice fit in the aperture 53 of the lug 52. A recess 63 having tapered walls 64 is formed in the underside of the wrist portion 62 of the barrel and is adapted to lie substantially opposite the aperture 60 of the lug when the barrel has been assembled therein. The barrel fastening bolt 61 is provided with a frusto-conical end 65 which is adapted to project into the recess 63 initially to engage the rear tapered walls 64 thereof. By turning the bolt up, a camming action is set up between the mutually engaging surfaces of the bolt and barrel recess to draw the wrist portion of the barrel rearwardly into the lug until the barrel shoulder 62' brings up tightly against the front face of the lug. It will be noted that when the barrel is secured in the barrel lug 52, the rear end of the fore-stock 21 is brought adjacent the front face of the lug. To increase the rigidity of the joint between the barrel and receiver, the rear end of the fore-stock 21 may be provided with a tongue portion 66 adapted to engage the front face of the lug. The upper surface of the tongue may be bevelled as at 67 so as to engage the bevelled surface 59 of the lug while the bottom edge 68 of the tongue 66 may be adapted to overlie the front edge of the bottom 42 of the trigger plate.

The trigger plate cover 26 is a trough-shaped member formed from sheet metal and comprises spaced substantially parallel side walls 69 and a top wall 70. The latter is provided with a tapered profile at its rear end to form a smooth unbroken curve with the pistol grip of the butt stock and a bevelled front edge. Welded or otherwise fastened to the underside of the top wall 70 adjacent the forward end thereof is a receiver insert 72 comprising a substantially rectangular metal plate curved transversely to fit the contour of the top wall and having substantially square shoulders 73 and 74 at its opposite ends respectively. When the cover 26 is assembled on the trigger plate 25, the forward shoulder 74 is adapted to abut the rear wall of the barrel lug insert 52. The rear shoulder 73 of the lug constitutes a firing pin stop for the purpose herein-after described.

Referring to Figs. 2, 6 and 7, the cover 26 is assembled on the trigger plate by slipping the side walls 69 of the cover down over the side walls 27 of the trigger plate. Suitable means are provided for locking the cover to the trigger plate and comprise longitudinal rectangular recesses 75 formed on the inside walls of the sides 69 of the cover and intersecting the rear edges thereof. By pushing the cover downwardly and rearwardly over the trigger plate, the recesses 75 are adapted to engage the substantially rectangular projections 40 on corresponding sides of the trigger plate and to effectively lock the rear end of the cover thereto. The forward end of the cover is fastened to the trigger plate by means of a transverse pin 76 which is adapted to pass through

axially aligned apertures in the sides of the cover and in the barrel lug insert. In assembling the barrel 23 to the receiver, the receiver pin 76 is first inserted in its apertures so as to fasten the cover to the trigger plate and then the barrel locking screw 61 is secured in the tapped hole of the barrel lug insert for securing the barrel therein. The shank of the screw 61 is adapted, as shown, to engage in a circumferential groove intermediate the ends of the pin 76 to lock the latter in the receiver. As shown in Fig. 1, the right side of the receiver cover 26 is provided with a cartridge ejecting aperture 71 which is located adjacent the top of the receiver and extends longitudinally thereof.

The butt stock 20 is secured to the receiver 22 by means of a bolt 78 which is supported in the stock bolt stud 36 and threadedly secured at its rear end in the tapped hole of a bushing 79 which in turn is threadedly secured in a recess in the stock. The forward end of the stock is reduced to provide a tongue portion 82 and shoulder 83. The latter is adapted to abut the rear ends of the cover and trigger plate which, as shown, extend rearwardly of the rear wall 29 of the receiver to form a seat or recess in which the tongue portion 82 of the stock makes a snug fit.

Mounted in the receiver is a breech block 84 comprising a substantially rectangular block of metal adapted to be slidably supported on the upper edges 27' of the trigger plate, see Fig. 4. The bottom 85 of the breech block is provided with a substantially rectangular slot 86 to provide clearance for the upper end of the magazine and the cartridge carrier as hereinafter described, the longitudinal axis of the slot being coincident with the longitudinal axis of the breech block. The slot extends from the front end of the breech block to a point to within a short distance from the rear end thereof. A relatively narrow clearance groove 87 is formed in the rear end of the groove 86, the longitudinal axis of the clearance groove 87 being coincident with that of the first groove and adapted to provide clearance for a cartridge stop member as described below. A relatively short narrow slot 88 is shown at the rear end of the breech block adjacent the right-hand edge thereof, see Figs. 8 and 9. The rear end of the right-hand wall of the slot 88 is bevelled as at 89 to provide a cam surface for actuating a cartridge carrier latch. As shown in Fig. 4, the top of the breech block is provided with a substantially rectangular guide groove 90 which extends throughout the length of the breech block, as shown in Fig. 6. When the breech block is mounted in the receiver, the receiver insert 72 is adapted to project into the guide groove 90. It will be noted that both the receiver insert and breech block groove are slightly to the right of the longitudinal center line of the receiver.

Extending through the breech block from its rear end forwardly to a point adjacent the front end thereof is a firing pin aperture 92, the longitudinal axis of which is substantially parallel to the longitudinal axis of the groove 90. The rear end of the firing pin aperture opens into the groove 90 of the breech block and provides a substantially rectangular aperture 93 having a square shoulder 94. The forward end of the aperture 92 terminates short of the front face of the breech block in an aperture 92' which is of reduced diameter and adapted to receive the firing pin needle 103'. A second aperture 95 is formed at the right-hand side of the breech block, its longitudinal axis being substantially parallel to that

of the aperture 92. The aperture 95 is adapted to receive an action spring, indicated at 96 in Fig. 5 and terminates at its forward end in a semicircular groove 97 and shoulder 98, as shown in Fig. 10. A relatively narrow transverse slot 99, see Fig. 4, is formed in the side of the breech block adjacent the front end thereof for receiving an extractor. The slot 99 opens at its rear end into the forward end of the aperture 95. Depending from the forward end of the breech block is a lug or thumb piece 100 which in the present embodiment is a U-shaped member struck up from sheet metal stock and welded or otherwise secured to the bottom of the breech block. The lower end of the thumb piece is contoured as at 102 and provided with knurling to facilitate manual displacement of the breech block rearwardly in the receiver.

A firing pin 103 is slidably mounted in the aperture 92 of the breech block and comprises a substantially cylindrical member having a firing pin needle 103' at its forward end. Adjacent the rear end of the firing pin is a lug 104 substantially rectangular in cross section and adapted to project upwardly through the opening 93 in the breech block. The front face of the lug 104 comprises a substantially vertical shoulder 105 adapted as hereinafter described to abut the shoulder 73 of the receiver insert and the shoulder 94 of the breech block opening 93. A suitable notch 106 is provided on the rear end of the firing pin to be engaged by a sear member. The firing pin is apertured longitudinally to receive a coil main spring 107, see Fig. 7, having a pilot 108 at its rear end provided with a recessed head 109. The action spring 96 is mounted in the aperture 95 of the breech bolt and is provided at its forward end with a recessed button 1090 and at its rear end with a substantially cylindrical pilot 110. The latter is reduced at its rear end to provide a nipple 1101 adapted to be received in an aperture 1102 in the rear wall of the receiver, as shown in Fig. 5. Rearward movement of pilot is prevented by engagement of the shoulders of the nipple with the edges of the aperture 1102. The recess of the button 1090 is adapted to receive the nub 111 of an extractor 112, see Figs. 5 and 10, which is freely supported in the transverse slot 99 of the breech bolt and comprises a hook 113 at its rear end adapted to engage behind the shoulder 98 of the semicircular groove 97 and to fulcrum in the semicircular groove 97. A suitable hook 114 is provided on the forward end of the extractor to engage the rim of a cartridge 55 in the usual manner.

A cartridge carrier is indicated generally at 115, see Figs. 11 and 12, and comprises two spaced substantially parallel sheet metal side members 116 joined together at their rear ends by a bridge 60 116', each side member having a suitable trunnion 117 and 117' respectively secured thereto by a screw 118 adjacent its rear end and projecting laterally therefrom. The trunnions are adapted to be rotatably mounted in the corresponding slots 28 in the sides 27 of the trigger plate to pivotally support the carrier therein, the outer ends of the trunnions being substantially flush with the outer faces of the respective sides 27. The trunnion 117 is adapted also, together 65 with suitable rivets, to securely fasten the forward end of a carrier latch arm 119 to the carrier. The carrier latch arm comprises a thin spring steel member having a latch block 120 fastened at its rear end adjacent the upper edge thereof. 70 75 The outside of the latch block is provided with a

substantially square shoulder 122, see Fig. 8, adapted normally to be held in engagement with the upper edge 27' of the adjacent wall 27 of the trigger plate by the inherent resiliency of the arm 119 to lock the carrier against pivotal movement. The forward end of the block is provided with a bevelled or cam surface 123, see Figs. 9 and 11, which is adapted to be engaged by the cam surface 89 of the breech block when the latter reaches its rearmost position in the receiver to cam the shoulder 122 of the latch block 120 off of the edge 27' of the trigger plate thereby to unlatch the pivoted carrier 115.

Supported between the sides of the carrier is a cartridge stop 123 comprising a convex sheet metal member pivotally mounted on the inner ends of the screws 118 of the trunnions 117 and 117' by means of its rearwardly extending arms 124. The cartridge stop is provided at its forward end with a block 125 which may be secured by welding in a slot on the longitudinal axis of the stop member or may be an integral part of the stop member. The upper edge of the block 125 provides an upwardly projecting rib portion 126 while its lower edge constitutes a bevelled cartridge engaging shoulder 127, see Figs. 6 and 7, adapted to extend into a slot 128 in the upper end of the tubular magazine 24. The rib portion 126 is adapted to be engaged by the top of the slot 86 of the breech block when the action is open and to be positively held down thereby so that the bevelled shoulder 127 will be held against the rim of a cartridge in the upper end of the magazine. When the breech block is in its forward position, see Fig. 7, the rib portion 126 of the block 125 is opposite the slot 87 in the rear end of the breech block, and hence is free to move upwardly therein. The force of the magazine spring, not shown, is thus enabled to push a cartridge past the bevelled shoulder 127 of the pivoted stop 123 into the cartridge carrier 115.

The forward end of the cartridge carrier is provided with resilient fingers 129 and 130 for firmly grasping the cartridge as it is fed from the magazine.

Referring to Figs. 11 and 12, the fingers are extensions of the sides of the carrier and are arranged in spaced parallel substantially vertical planes, each finger having an outwardly flared portion 132 and 133 respectively on its upper edge which effectively closes up any space between the sides of the trigger plate and the fingers. This precaution is taken to prevent an extracted case from falling down into the trigger plate and becoming jammed therein. Both fingers are also provided with longitudinal ribs 134 and 135 respectively on the inner upper edges thereof to form a slight restriction in the space between the fingers so that a cartridge therein will not inadvertently slip or jump out of the fingers.

The fingers are held in spaced parallel relationship by means of a spacer comprising a plate, indicated generally at 136, which is L-shaped in cross section, one leg 137 of the plate being fastened by rivets or welded joints to the inside of the finger 129 adjacent the lower edge thereof. The other leg 138 of the spacer plate lies in a substantially horizontal plane between the two fingers and serves to support a cartridge therein and to keep the finger 130 at a predetermined distance from the finger 129.

Referring to Figs. 6 and 7, the rear end of the spacer plate 138 has an extension 138' which is

bent downwardly at substantially right angles to form a stop for the carrier spring hereinafter described.

Due to the inherent resiliency of the sides of the carrier, they may be sprung apart slightly to enable a cartridge to enter between the fingers onto the supporting plate 138. To prevent inadvertent separation of the fingers and to augment the inherent resiliency thereof, a coil spring 139 is provided which is mounted on the shank of a screw 140. The shank of the screw passes freely through a hole in a bracket 142 formed integrally at the front end of the finger 130. The spring 139 is confined between the head of the screw 140 and the bracket 142, the threaded end of the screw 140 being secured in axially aligned tapped holes in the leg 137 and the downwardly extended end of the finger 129. As shown in Fig. 6, the rear edges of the resilient fingers slope downwardly and constitute cam surfaces 143 and 144 respectively adapted to be engaged by the forward end of the breech block. The carrier is urged at all times to pivot counterclockwise so as to carry the resilient fingers up into the path of the breech block by means of a spring 145, the forward end of which engages the stop 138' of the spacer plate 138. The spring 145 is a combination trigger spring, cartridge carrier spring and safety spring as more particularly described below. When the breech bolt approaches its chamber closing position, it engages the cams 143 and 144 of the carrier and pivots the carrier downwardly out of the path of the breech bolt. Simultaneously, the breech bolt engages and pushes a cartridge out of the fingers of the carrier into the chamber of the barrel. In the foremost position of the breech bolt in the receiver, the forward edges of the resilient fingers 129 and 130 of the carrier engage the rearwardly extending ledge 58 of the barrel insert lug which holds the resilient fingers firmly substantially opposite the end of the tubular magazine 24 to enable a cartridge to be fed therefrom into the fingers, see Fig. 7. When the breech block moves rearwardly, the carrier is unlatched in the manner described above, and hence is pivoted counterclockwise by the spring 145. By the time the breech block is in its rearmost position in the receiver, the carrier has risen to its uppermost position in the receiver, which position is attained by displacement of the sides of the carrier 115 up into the groove 86 in the bottom of the breech block. In its uppermost position, the resilient fingers of the cartridge support the cartridge in substantially axial alignment with the barrel chamber, as shown in Fig. 6.

Referring to Fig. 13, the fire control mechanism embodies a sear, indicated generally at 146, comprising a relatively wide hook 147 having a bifurcated wall portion 148 at its rear end extending downwardly at substantially right angles thereto. Formed integrally on the bifurcated rear wall 148 are spaced parallel flanges 149 shaped substantially like the inverted truncated right angle triangle and somewhat thinner than the bifurcations of the rear wall 148 so as to form substantially square shoulders 150 therewith. Two pairs of axially aligned holes 152 and 153 are formed transversely in the upper and lower portions respectively of the flanges 149.

The flanges are adapted to make a nice fit between the aforementioned bracket members 32 of the rear wall of the receiver and to be pivotally connected therein by means of a pin 154 which

is adapted to pass through the axially aligned apertures 152 and 33 of the flanges and brackets respectively. The forward end of the sear hook 147 has a slightly bevelled surface 147' which is adapted to engage a corresponding bevelled surface 106' on the rear end of the firing pin and to be cammed counterclockwise thereby out of the path of the firing pin. The sear hook 147 is thus elevated above the notch 106 of the firing pin as the latter moves to its rearmost position in the receiver. When the firing pin moves forwardly, the sear hook 147 is pivoted downwardly or clockwise by the force of the compressed main spring as hereinafter described to engage in the notch 106 of the firing pin. After release of the firing pin, the sear pivots downwardly, its clockwise movement being stopped by engagement of the shoulders 150 of the sear with the forward edges of the brackets 32.

Supported by means of a pin 155 in the holes 153 of the sear is a sear disconnector, indicated generally at 156, comprising a link portion 157 having an aperture 157' to receive the pin 155 for pivotally mounting the link between the spaced webs 149 of the sear. A substantially vertical finger 1570 projects forwardly from the upper end of the link 157 between the bifurcated rear wall portion 148 of the sear and is adapted to take into the recessed head 109 of the spring pilot 108. The disconnector link is provided at its lower end with an arm 158 which is bent at substantially right angles to the plane of the link. The arm is in turn provided with a reach 158' bent at substantially right angles to the arm 158 so as to lie in a plane substantially parallel to the plane of the link 157. The reach 158' is provided at its outer or forward end with an enlargement 159 having a cam surface 159' adapted to be held up in the path of the breech bolt by the force of the main spring 107 acting through the pivoted link 157 and to be displaced downwardly by engagement with the bottom of the breech block when the latter moves rearwardly for the purpose hereinafter described.

Rearwardly of the enlargement 159 and extending downwardly from the bottom edge of the reach is a shoe 160 having a toe 162 and a heel portion 163. The latter has a substantially square end having a relatively oblique smooth flat surface 163' spaced from the bottom edge of the reach 158' by a notch 1630. The upper edge 162' of the toe 162 is substantially parallel to the reach 158' and spaced from the underside of the enlargement 159 by a space 164.

Referring to Figs. 3, 6, 7 and 8, the foot 160 and, in particular, the toe portion 162 of the disconnector are adapted to be held against the left-hand wall of the trigger plate in sliding engagement therewith by means of a combination guide and disconnector stop. The latter comprises a button 165 having a shank 166 suitably secured in a hole in the left-hand side of the trigger plate. The shank 166 is located in the notch 164 of the disconnector and is adapted to be engaged by the upper edge 162' of the toe 162 to limit the upward movement of the disconnector about its pivot pin 155. The button 165 overlies the inside face of the toe 162 so as to guide the forward end of the disconnector. The disconnector is displaced downwardly as described above by engagement of the breech block with the cam surface 159' of the disconnector. The disconnector is also adapted to be displaced, and, in this instance, substantially longitudinally by the action of the trigger as hereinafter described.

The trigger is indicated generally at 167 and comprises a substantially rectangular flat bridge 167' having a vertical flange 168 at its right-hand edge, see Fig. 13, and a longer vertical flange 169 at its left-hand edge, each flange being provided with a transverse hole 170 both of which are in axial alignment.

The left-hand flange 169 is provided at its upper edge with a finger 172 having a substantially flat smooth relatively oblique surface 172' adapted to engage the corresponding oblique surface 163' of the disconnector 156. Extending forwardly from the front edge of the bridge 167' of the trigger and at substantially centrally thereof are a pair of spaced parallel fingers 173, each having a transverse hole 174 both of which are in axial alignment. The trigger 167 is pivotally mounted in the trigger plate by means of a pin 175 which passes through the apertures 170 of the fingers 168 and 169 and is supported at its opposite ends in suitable apertures in the walls of the trigger plate. The finger engaging portion of the trigger extends through the slot 43 in the bottom of the trigger plate. When the cover of the receiver is assembled on the trigger plate, its sides overlie the ends of the trigger pivot pin 175 to lock the pin in place. The holes 174 of the fingers 173 are adapted to receive a pin 176 which passes through the eye 177 of the aforementioned carrier, trigger and safety spring 145. The pin 176 is adapted to secure the eye of the spring 145 between the fingers 173 of the trigger. The spring 145 is a substantially flat spring steel member having a V-shaped fulcrum 145' adjacent its rear end and a reach which extends forwardly through the aperture 47' of the web 46 and is adapted to engage the stop 138' of the carrier.

The spring fulcrum 145' is adapted to rest on the upper surface of the trigger locking means or safety indicated generally at 182. The latter comprises a slightly concave substantially rectangular member guided between the sides of the trigger plate on the bottom thereof and between the trigger and the substantially vertical magazine supporting web 46. The safety is held in its "off" position by means of a protuberance 183 which, in the "off" position of the safety, is in front of the fulcrum 145' of the spring 145. The safety is provided with a rearwardly extending tang 184 which is bent downwardly at its rear end so as to extend into the relatively narrow guide slot 44 in the bottom of the trigger plate. The lower end of the tang is provided with a finger grip 185. By pulling the grip 185 rearwardly to its "on" position, suitable shoulders 182' at the rear edge of the safety member 182 are moved beneath the bottom edges of the fingers 173 of the trigger so as to effectively lock the trigger. As the safety slides rearwardly, its protuberance 183 forces the fulcrum 145' of the spring upwardly and over to the opposite side of the protuberance. The safety is thus effectively held in its "on" position by the resilient force of the spring.

The operation of the action of the firearm may be described briefly as follows: Assuming a cartridge has just been fired, the action is closed, and the breech block 84 and firing pin 103 are in their forward positions in the receiver as shown by the full lines in Fig. 7. The needle 103' of the firing pin has advanced sufficiently in the breech block to form an indenture in the rim of the fired cartridge. It will be noted, however, that the firing pin 103 has not reached its

foremost position in the breech block 84 but has been stopped short of this position by engagement of the shoulder 105 of the firing pin lug 104 with the shoulder 73 of the receiver insert 72. Assuming the trigger 167 has been released by the shooter's finger, the trigger finger 172 has been pivoted rearwardly from the dotted line position which corresponds to its firing position to its full line position by the force of the combination carrier, trigger and safety spring 145 acting on the pin 176. Moreover, the force of the main spring 107 acting on the finger 157 of the disconnector link 157 has pivoted the sear hook 147 downwardly in which position its shoulders 150 engage the front edges of the bracket 32 as hereinabove described. The disconnector 151 has simultaneously participated in substantially longitudinal movement rearwardly due to the force of the main spring 107 such that the enlargement 159 of its reach has moved rearwardly slightly and cleared the rear end of the breech block. The oblique surface 163' of its heel 163 thus maintains its engagement with the corresponding rearwardly moving oblique surface 172' of the trigger finger 172. The cartridge carrier 115 has been pivoted downwardly by the previous advance of the breech block so that its resilient fingers 129 and 130 are opposite the open end of the magazine 24 from which a cartridge A has been released and fed into the fingers. The next succeeding cartridge B in the magazine 24 is held between the cartridge A and the next succeeding cartridge or magazine spring pilot and is momentarily free of the shoulder 127 since the rib 126 of the stop 123 is opposite the clearance slot 87 in the bottom of the breech bolt, and hence is free to pivot upwardly. The force of the magazine spring acting on the spring pilot or the next succeeding cartridge will suffice to pivot the stop upwardly, and to disengage its shoulder 127 from the rim of the cartridge. However, as soon as the breech bolt begins to move rearwardly, it will be evident that the stop 123 will be forced downwardly, its shoulder 127 being engaged positively against the rim of the cartridge B in the end of the magazine. The carrier 115 is positively held in this downward position by engagement of the latch block 120, see Fig. 6, with the upper edge 27' of the trigger plate. The hook 114 of the cartridge extractor 112, see Fig. 10, is engaged in the usual manner with the rim of the fired cartridge, the extractor hook being resiliently urged into engagement with the rim of the cartridge by the force of the action spring 96 acting against the nub 111 of the extractor.

Following the firing of the cartridge, the residual pressure of the gases forces the breech block 84 rearwardly in the receiver, the fired case being withdrawn from the chamber by the extractor 112 and held firmly thereby on the front face of the breech bolt. The initial rearward movement of the breech bolt is accomplished without a corresponding movement of the firing pin since the shoulder 105 of the firing pin is spaced rearwardly a predetermined distance from the shoulder 94 of the breech bolt by the instrumentality of the receiver insert lug 72.

As a consequence of the relative movement of the breech block and firing pin 103, the protrusion of the needle 103' of the firing pin from the face of the breech bolt is increased. The needle 103' is, as shown in Fig. 4, on the side of the breech bolt substantially opposite the extrac-

5 tor and due to the force of the compressed main or firing pin spring 107 acting on the needle 103', the fired case is subjected to a force tending to pivot it laterally. Hence, as soon as the breech bolt has moved rearwardly sufficient for the open end of the fired case to clear the chamber end of the barrel, the fired case will be freed and flipped sharply out of the ejection port 77 on the side of the receiver. This action may be augmented by 10 a slight pivotal movement of the extractor about its fulcrum 113 in the semicircular groove 96 in the main spring aperture 95.

Moreover, as soon as the breech bolt starts back, its rear end engages the cam surface 159' 15 of the sear disconnector 156 pushing it downwardly. The disconnector heel 163 is thereby disengaged from the trigger finger 172, the latter then being opposite the notch 1630 whereby the trigger is disconnected from the sear. When the breech block approaches the rear end of the receiver, its cam surface 89 engages and cams the latch block 120 off of the upper edge 27' of the trigger plate, thereby releasing the carrier 115 20 which is immediately pivoted upwardly by the force of its spring 145 carrying the cartridge A in its resilient fingers into substantially axial alignment with the chamber of the barrel, as shown in Fig. 6. The breech block is finally brought to a stop against the rear wall of the receiver. The sear hook 147 has been urged upwardly against the restraining force of the main spring 107 by engagement with the bevelled surface 106' of the firing pin, pivots upwardly as hereinabove described and extends over the notch 30 106 of the firing pin. As the breech block 84 and firing pin 103 are started forwardly by the forces of the compressed action spring 95 and main spring 107, the sear hook 147 snaps into the notch 106 of the firing pin 103 and holds it in its rearward or cocked position as shown by the 35 dotted lines in Fig. 7. As the breech block continues under the force of the action spring 95, the forward end of the breech block engages and rides over the cam surfaces 143 and 144 of the carrier forcing the unlatched carrier downwardly. Simultaneously, the face of the breech bolt engages the end of the cartridge A and pushes it forwardly in the fingers of the carrier so that the nose of the bullet enters the barrel chamber. As the breech bolt continues to chamber closing 40 position, the resilient fingers of the carrier are stripped off of the cartridge as the latter is advanced and chambered in the barrel. Throughout the rearward and forward movements of the breech block, the cartridge stop 123 has positively held the cartridge B at the end of the magazine 24. However, as soon as the action is closed, the stop 123 is released and permits the cartridge B to automatically feed into the resilient fingers of 45 the carrier. The protuberance 159 of the sear disconnector has again been disengaged by the breech block and is pivoted upwardly by the force of the compressed main spring 107 to reengage its heel 163 with the trigger finger 172. The gun is now in cocked position and ready to be fired.

50 If the safety finger 185 is in its forward position, as shown in Fig. 7, the trigger is free and may be pulled rearwardly whereupon the finger 172 moves forwardly forcing the sear disconnector 156 forwardly in a substantially longitudinal direction to the advanced position, indicated by the dotted lines in Fig. 7. The forward draft of the disconnector causes the sear to pivot counterclockwise, and hence to disengage the sear hook 147 from the notch 106 of the firing pin which

immediately springs forward in the breech block and fires the cartridges in the barrel chamber. The cycle of extraction, ejection, recocking and reloading are then automatically repeated. In the event the trigger is held back after being pulled, the bevelled surface 172' of its finger 172 is held against the bevelled surface 163' of the disconnector in the position shown by the dotted lines in Fig. 7. Then as the breech block moves rearwardly and engages the protuberance 159 of the disconnector, its bevelled surface 163' is moved downwardly out of engagement with the trigger finger, as shown in Fig. 6, the respective bevelled surfaces 163' and 172' having slopes to permit the bevel 163' to slide freely by the bevel 172'. The trigger finger 172 is thus opposite the notch 1630 of the disconnector and hence incapable of actuating the sear.

What is claimed is:

1. In an automatic firearm comprising a receiver, a breech block reciprocably mounted in said receiver; a firing pin slidably mounted in said breech block; resilient means for actuating said firing pin; fire control mechanism for cocking and releasing said firing pin comprising a sear pivotally supported in said receiver; a connector pivoted to said sear, said connector being engaged by said resilient means and provided with a finger portion; and a trigger pivoted in said receiver having a finger portion arranged normally to engage the finger portion of said connector, said sear being held in a normal position in cocking engagement with said firing pin by the force of said resilient means acting on said connector.

2. In an automatic firearm comprising a receiver, a breech block reciprocably mounted in said receiver; a firing pin slidably mounted in said breech block; resilient means for actuating said firing pin; fire control mechanism for cocking and releasing said firing pin comprising a sear pivotally supported in said receiver; a connector pivoted to said sear, said connector being engaged by said resilient means and provided with a finger portion; and a trigger pivoted in said receiver having a finger portion arranged normally to engage the finger portion of said connector, said finger portions of said connector and trigger being held normally in engagement by the force of said resilient means acting on said connector which force is adapted also to resiliently hold the sear in a normal position in cocking engagement with said firing pin.

3. In an automatic firearm, a receiver, a breech block reciprocably mounted in said receiver; a firing pin slidably mounted in said breech block; a coil spring carried by said breech block for actuating said firing pin, said coil spring having a pilot provided with a recessed head; fire control mechanism for cocking and releasing said firing pin comprising a sear pivotally supported on the rear wall of said receiver, said sear having a hook arranged normally to engage and cock said firing pin; a connector pivotally supported on said sear, said connector being provided with a boss seated in the recessed head of

said pilot and having a forwardly extending reach provided with a foot portion; guide means secured to the wall of said trigger plate to guide said reach; and a resiliently mounted trigger pivotally supported in said trigger plate, said trigger having a finger portion arranged normally to contact the foot portion of said connector and to move said connector forwardly when said trigger is pulled to move said sear and release said firing pin.

4. In an automatic firearm comprising a receiver; a breech block mounted in said receiver and reciprocable from chamber open to chamber closing positions therein; a firing pin resiliently mounted in said breech block; fire control mechanism for cocking and releasing said firing pin comprising a sear pivotally mounted in said receiver; a trigger pivotally mounted in said receiver; a connector pivotally supported on the sear, said connector having a forwardly extending reach provided with a finger arranged to engage said trigger and a protuberance, said protuberance being arranged to be engaged by said breech block for all positions of said block rearwardly of its chamber closing position to positively hold said trigger engaging finger out of engagement with said trigger; and resilient means for normally biasing the trigger engaging finger of said connector in engagement with said trigger.

5. In an automatic firearm, a receiver; a breech block reciprocable in said receiver; a firing pin carried by said breech block; fire control means comprising a pivoted sear and sear connector for holding said firing pin in cocked position in said breech block and for releasing said firing pin; fastening means carried by said pivoted sear to pivot said connector thereto; and a spring in said breech block adapted to engage said firing pin to urge said firing pin forwardly in said breech block, said spring being arranged to cooperatively engage said connector to enable said sear to hold said firing pin in cocked position in said breech block.

Certificate of Correction

Patent No. 2,425,412.

August 12, 1947.

CHARLES H. BARNES

It is hereby certified that error appears in the printed specification of the above numbered patent requiring correction as follows: Column 2, line 33, for the patent number "1,038,384" read 1,083,384; and that the said Letters Patent should be read with this correction therein that the same may conform to the record of the case in the Patent Office.

Signed and sealed this 7th day of October, A. D. 1947.

[SEAL]

THOMAS F. MURPHY,
Assistant Commissioner of Patents.
